Atty.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,387,112.

Specification of Letters Patent. Patented Aug. 9, 1921.

Application filed January 16, 1920. Serial No. 351,777.

To all whom it may concern:

Be it known that I, FRED S. CARR, a citizen of the United States, and a resident of Newton, in the county of Middlesex, Commonwealth of Massachusetts, have invented an Improvement in Fasteners, of which the following description, in connection with the accompanying drawings, is a specification, like characters on the drawing representing like parts.

This invention pertains to improvements in separable fasteners, and more particularly, though not exclusively to dress fasteners of the type adapted to be sewed to the fabric.

It is among the objects of my invention to provide a fastener in which a stud and socket may either be adapted to be locked against separation under lateral strain, for use on heavy fabrics or which, optionally, may be adapted not to lock under lateral strain, for use on light fabrics.

The disclosure of the present application resembles closely that shown in my copending application, Serial No. 351,776, filed herewith, differing therefrom in that the socket is reversible, the socket when applied with the disk portion thereof away from the fabric providing for a lock under lateral strain, and when applied with the flanged side of the socket away from the fabric, providing a fastener not locked against separation by a resolution of forces arising from lateral strain between stud and socket.

In the drawings which show a preferred form of one embodiment of my invention:—

Figure 1 shows two pieces of fabric secured together by a dress fastener;

Fig. 2 is a section on the line 2—2 of Fig. 1, where the socket is applied to the fabric in such a way as to provide a lateral lock;

Fig. 3 shows two pieces of fabric secured together by a plurality of such fasteners;

Fig. 4 is a plan view of a preferred form of socket for use in connection with my invention; and

Fig. 5 is a section on the line 2—2 of Fig. 1, where the socket is applied to the goods in such a way as not to provide a lateral lock against forces resultant from lateral strains between stud and socket.

Referring to the drawings and to the preferred form of my invention selected for illustrative purposes, I preferably provide a stud 6 which may have a base, a head

and a neck of the usual character adapted to be sewed to the fabric 7. The socket is preferably of the type in which a disk 8 has flanged marginal portions 9 to hold in the socket a spring 10. The preferred form of socket herein illustrated is similar to that shown in my copending application above referred to, having an aperture 11 therein preferably provided with notches 12, the spring 10 preferably being diagonally positioned so that when the socket is applied as shown in Fig. 2 with the disk portion of the socket casing away from the fabric to which the socket is attached, and adjacent the base of the stud, lateral strains will tend to cause the neck of the stud to enter the notches 12, 12 and become wedged there as more fully described in my copending application, in such a manner that while the stud and socket will be locked together against any strain resultant from lateral strains on stud and socket, the stud and socket may be separated by a strain at a greater angle than that resolved from a lateral strain.

When, however, the socket is sewed to the socket-carrying fabric 13 in the manner shown in Fig. 5 with the plate portion of the socket adjacent the fabric 13, the springs 12 will engage the neck of the stud in the same manner as shown in Fig. 2, but the apertured plate having the notch therein will not be effective as a lock and, if substantial strain is exerted between stud and socket in a lateral direction, the stud and socket will separate.

It will be understood that while for most fabrics it is highly desirable to provide a lock against lateral strain, it may in some instances, for light fabrics or laces, be desirable to provide for separation of stud and socket by a strain somewhat less than that which might tear the fabric.

While I have shown and described a preferred form of one embodiment of my invention, it will be understood that changes may be made, including omission, substitution, alteration and reversal of parts, or even changes in the mode of operation, without departing from the scope of my invention, which is best defined in the following claims.

Claims:

1. A separable fastener comprising, in combination, a stud and socket including a plate having flanged marginal portions, a

spring retained in said socket beneath said flanged marginal portions, an aperture in said plate providing a narrowed portion at one side of said aperture, said stud and socket being proportioned to permit engagement of said stud with said spring from either side of said socket.

2. A separable fastener comprising, in combination, a stud and socket including a 10 plate having flanged marginal portions, a spring retained in said socket beneath said flanged marginal portions, an aperture in said plate providing a narrowed portion at one side of said aperture, said stud and 15 socket being proportioned to permit engagement of said stud with said spring from either side of said socket, said spring providing opposed stud-engaging portions extending diagonally of the major diameter of 20 the aperture in said plate.

3. A separable fastener comprising, in combination, a stud and socket including a plate having flanged marginal portions, a spring retained in said socket beneath said 25 flanged marginal portions, an aperture in said plate providing notches, said stud and socket being proportioned to permit engagement of said stud with said spring from either side of said socket.

30 4. A separable fastener comprising, in combination, a stud and socket including a plate having flanged marginal portions, a spring retained in said socket beneath said flanged marginal portions, and an aperture 35 in said plate providing notches, said stud

and socket being proportioned to permit engagement of said stud with said spring from either side of said socket, and said spring providing opposed stud-engaging portions extending diagonally of the notched aperture in said plate. 40

5. A separable fastener comprising, in combination, a stud having a head and a neck coöoperating with a socket having a plate containing a spring, said plate providing at 45 one side of the socket a relatively small aperture through which the head of the stud may be passed and providing as a part of said aperture a narrowed portion, the walls of which oppose separation of stud and 50 socket by strain exerted at any angle resultant from lateral strain between said stud and socket in a direction toward said narrowed portion, while permitting ready separation of stud and socket by force exerted 55 at an angle greater than that which is likely to result from lateral strain, the opposite side of said socket and the coöperating portions of said stud being adapted to permit engagement of stud and socket while said 60 narrowed portion is rendered ineffective to oppose separation under lateral strain, thereby to provide at the option of the user a fastener providing either a very great or a comparatively small resistance to separation by 65 forces resultant from lateral strain.

In testimony whereof, I have signed my name to this specification.

FRED S. CARR.
